UNITED STATES PATENT OFFICE.

GEORGE A. GUMPHERT, OF PHILADELPHIA, PENNSYLVANIA, ASSIGNOR OF ONE-HALF TO THOMAS MARRIN, OF SAME PLACE.

SHAKING-GRATE.

SPECIFICATION forming part of Letters Patent No. 600,493, dated March 8, 1898.

Application filed November 6, 1897. Serial No. 657,632. (No model.)

To all whom it may concern:

Be it known that I, GEORGE A. GUMPHERT, a citizen of the United States, residing in the city and county of Philadelphia, State of Pennsylvania, have invented a new and useful Improvement in Shaking-Grates, which improvement is fully set forth in the following specification and accompanying drawings.

My invention consists of an improved construction of shaking-grate, in which provision is made for effectively shaking every portion of the grate-surface either simultaneously or at different periods, means being provided when all the grate-sections are shaken simultaneously for rocking or oscillating adjacent slice-bars mounted on the same bearing-bar in opposite directions, and provision being also made for rocking simultaneously every other series of slice-bars, while the intermediate slice-bars remain stationary or serve as dead-bars.

It also consists of a novel construction of slice-bars having a curved or serpentine strengthening-rib therein and curved, sinusous, or serpentine openings therethrough for the admission of air, the upper portion of the slice-bar being rounded and its sides between center and top below its top surface being provided with serrations or teeth, so that the refuse, clinkers, &c., which fall over either side of the slice-bars will be ground between each pair of adjacent bars, since when the latter are actuated simultaneously they rock or oscillate in opposite directions, especial attention being called to the fact that the function of the serpentine rib above referred to is to provide the necessary strength required in reinforcing the slice-bar, so as to enable said teeth to effectively perform their function.

It also consists of a novel construction of side bearing-bars, end frames, and key-blocks, by means of which the sections composing the outer framework of the grate are held in assembled position without necessitating the employment of bolts or other extraneous fastening devices, thus rendering the grate capable of being readily and expeditiously erected without necessitating the employment of skilled labor.

It also consists of novel means for strength-

ening and actuating the slice-bars and supporting and locking the actuating mechanism.

It further consists of novel details of construction, all as will be hereinafter fully set forth, and particularly pointed out in the claims.

Figure 1 represents a perspective view of a shaking-grate embodying my invention, showing the different positions the slice-bars can be caused to assume by the proper manipulation of the actuating-levers. Fig. 2 represents a top plan view of the grate, showing the two intermediate or central transverse rows or series of slice-bars seen in Fig. 5 removed and a substantially central tie-piece employed in their stead, the left-hand series of slice-bars being shown as simultaneously actuated, each adjacent pair of slice-bars being rocked in opposite directions. Fig. 3 represents a bottom plan view of Fig. 2. Fig. 4 represents a bottom plan view of a grate, showing especially the means for actuating or oscillating the slice-bars when the tie-piece seen in Figs. 1 and 2 is dispensed with. Fig. 5 represents a longitudinal section of Fig. 4, the same being taken on line *xx* of said figure and viewed in the direction of the arrows. Fig. 6 represents, on an enlarged scale, a transverse section on line *yy*, Fig. 2, showing the means for supporting, actuating, and strengthening the slice-bars. Fig. 7 represents a transverse sectional view of a single slice-bar in detached position, the section being taken on a different plane from Fig. 6. Fig. 8 represents a section on line *zz*, Fig. 2, showing the relative positions the slice-bars assume when they are simultaneously actuated. Fig. 9 represents an end view of the grate, showing the rocking-levers and the manner of assembling the head-piece or end frame, which latter is held locked in position by the key-blocks best seen in Fig. 2. Fig. 10 represents a perspective view of a slice-bar in detached position. Fig. 11 represents a perspective view of a cap and its adjuncts employed for strengthening or reinforcing the slice-bar seen in Fig. 10. Fig. 12 represents a side elevation of the lower portion of a slice-bar, showing the depending lugs of the latter and the cap seen in Fig. 11 applied thereto. Fig. 13 represents a top plan view

of the abutting ends of the side bearing-bars seen in Figs. 4 and 5. Fig. 14 represents a side elevation of Fig. 13. Fig. 15 represents a top plan view of a slice-bar similar to the bar seen in Fig. 10, but having transverse, sinuous, or serpentine webs and openings. Fig. 16 represents a section on line $x'x'$, Fig. 6.

Similar numerals and letters of reference indicate corresponding parts in the figures.

10 Referring to the drawings, 1 designates a shaking-grate, the same having an outer framework consisting of the side bearing-bars 2, which are preferably provided with serpentine grooves 2^x , which admit air therethrough.

15 3 designates the head-piece or front end frame, a similar end frame 3^x being employed at the opposite extremity of the grate, each of said end frames being provided with the tongues 4, which are of dovetail shape and 20 engage similarly-shaped recesses 5 in the key-blocks 6, it being noted that a portion of each dovetailed tongue 4 engages the similarly-shaped recess of the two adjacent key-blocks 6.

25 The two exterior key-blocks at either end of the grate are provided with extensions or tongues 7, which are seated in recesses 8 x , located at the end portions of the side bearing-bars 2, while it will be apparent from Fig.

30 9 that the dovetailed tongues 7^x in said figure engage the similarly-shaped grooves 9^x at the ends of the side bearing-bars 2, wherefrom it will be seen that the tongues and grooves 7^x and 9^x prevent the end frames 3 and 3^x from

35 upward or downward movement, while said end frames are prevented from endwise displacement by being interlocked with the blocks 6, said blocks preventing such endwise movement by reason of the engagement of

40 the tongues 7 with the grooves or pockets 8^x of the side bearing-bars 2, wherefrom it will be apparent that the entire outer framework can be readily assembled without employing bolts or other extraneous fastening devices

45 and also without necessitating the employment of skilled labor.

Each of the key-blocks 6 at either end of the furnace is provided with the serrations or teeth 8, which are adapted to coact with 50 the extremity of the adjacent slice-bars 14, whose construction in detail will be hereinafter referred to.

9 designates a tie-piece, which may or may not be employed, the same being best seen in Figs. 1, 2, and 3 and consisting of a suitable body portion 10, which has a rib 10^x depending from the under side thereof, said tie-piece being provided with the ports 11, which are arranged in staggered order, as will be understood from Fig. 2, or serpentine ports or openings may be employed, if desired, the upper portion of said tie-piece being slightly rounded or convex in order to prevent ashes, refuse, &c., from remaining on the top thereof. The extremities of the tie-piece are provided with the V or dovetail shaped tongues 12, which are adapted to seat or interlock in

similarly-shaped recesses 13^x , said tie-piece being thus held in position without necessitating the employment of bolts or other extraneous fastening devices.

70 The under portions 12 x of the longitudinal edges of the tie-piece 9 are slightly curved or arc-shaped and are provided with serrations 13, which are adapted to coact with the opposing curved faces of the adjacent slice-bars 14, as will be explained.

75 Each of the slice-bars 14 consists of a body portion 15, which has a convex top 15^x , the extent of the latter being understood from Fig. 10.

80 16 designates ledges which extend on either side of the slice-bars below the top thereof and terminate at a point intermediate its ends, said ledges or shoulders being provided with the serrations 17, whereby a series of teeth are formed on each side of the slice-bars which crush or grind the clinkers, refuse, &c., when a set of slice-bars are operated, as will be understood from Figs. 1, 8, and 10.

85 18 designates a serpentine rib or web which extends longitudinally of each slice-bar, said web having on either side thereof the curved ports 19 and 20, which are separated by the solid portion 20^x , ports 20 being preferably of less length than said first-mentioned ports 19, although this is not essential. It will be evident that the function of the serpentine rib is to give each slice-bar the necessary strength required, so as to prevent the collapsing thereof during the act of crushing the clinkers between a pair of adjacent bars.

90 When two sets or rows of slice-bars are employed, as seen in Figs. 2 and 3, the juxtaposed or adjacent ends 21 of the slice-bars are substantially rectangular to the top of the slice-bar, while the opposite ends 22 of the end slice-bars are curved or arc-shaped, so as to coact with the adjacent or juxtaposed faces of either the key-blocks 6 or the tie-piece 9, as will be understood from Fig. 8.

95 It will be seen from Fig. 10 that shoulders 23 and 24 are formed at each end of the slice-bar, which serve to temporarily catch the clinkers, &c., and retain the same during the act of crushing or grinding the same, which occurs when said slice-bars are actuated.

100 25 designates lugs depending from the slice-bars 14, whereby the space 27 is formed therebetween, the upper portion of said space being of polygonal shape, as indicated at 26, while the inner faces at the lower portion of said lugs are concaved, as indicated at 28.

105 29 designates caps or reinforcing devices, which are employed in conjunction with the lugs 25, said devices consisting of a plate or disk 30, which has the cylinder 31 projecting therefrom, said cylinder having the semicircular-shaped shell or cap 32 below, which is attached to the plate 30 and is adapted to contact with the lower or bottom surfaces 33 of the lugs 25 when the parts are assembled, as will be evident from Fig. 12, the cylinder 31 engaging the concavities 28, as is evident.

34 designates threaded openings in the cylinders 31, said openings being adapted for the reception of the screws or other fastening devices 39, which latter pass through the plates 5 38, whereby the caps 29 are held in position relative to the lugs 25.

The caps or reinforcing devices 29^X (seen in Fig. 6) are similar in all respects to the devices 29, except that the former have the bosses 35 projecting inwardly therefrom, each of said bosses having a squared or similar-shaped opening or pocket 36 therein for the reception of the rod or transmitter 37, as will be understood from Fig. 6.

15 40 designates bearing-bars employed, the same having the journals 41 at their extremities, which are adapted to rotate in the bearings 42 of the side bearing-bars 2, each of said bearing-bars extending transversely of the furnace and supporting a row of slice-bars thereupon, as is evident, and said bearing-bars 40 serving as an axis for alternate slice-bars, as will be explained.

43 designates dovetailed openings in the side bearing-bars 2, which extend from the top thereof to the point indicated in Fig. 6, said openings permitting the bearing-bars 40 to be dropped vertically into position, and ashes, clinkers, &c., being prevented from 30 falling upon the journals 41 after the dovetailed blocks 44 are inserted in place.

When the construction seen in Figs. 4 and 5 is employed, in which the central or intermediate tie-piece 9 is dispensed with, I preferably use the sectional side bearing-bars seen in Figs. 4 and 5 and having the interlocking devices best seen, on an enlarged scale, in Figs. 13 and 14, it being of course understood that the sectional side bearing-bars are also 40 adapted to be used with or without the central tie-piece, according to the length of grate desired. The bars on each side are made in sections 45 and 46, the section 45 having a tongue 47 projecting therefrom, said tongue 45 being provided with a head or T-shaped extremity 48, which latter is adapted to interlock in a seat or recess 48^X, while the tongue 47 is seated in the recess 47^X. The under side of the tongue 47 and the bearing-bar 45 50 are provided with a recess or step formed by the junction of the walls 49 and 50, which rest upon the legs 51 of the section 46, as will be understood from Fig. 14, it being thus apparent that the tongue 47 and head 48 are 55 supported upon said ledge, while said tongue and head are prevented from lateral displacement by means of their engagement with the similarly-shaped recesses 47^X and 48^X, provision being thus made for readily assembling said side bearing-bars, whereby the latter can be cast in a plurality of sections according to the length of grate desired, and it will further be apparent that by providing sufficient play for the tongue-and-groove connections, as indicated in Figs. 13 and 14, provision is made for expansion under all conditions; but said bars are prevented from lat-

eral vertical or longitudinal displacement by reason of the interlocking devices above specified.

70 51^X designates a connecting-rod which is adapted to actuate a row of slice-bars, as will be understood, from the right-hand side of Fig. 6 and the upper portion of Fig. 3, the connecting-rod 51^X being secured to the cylindrical portion 31 of the reinforcing devices 29^X, and thus when secured in place serving to hold said reinforcing devices in proper position relative to the lugs 25.

52 designates lugs or ears projecting from a slice-bar near the head-piece 3, as will be understood from Figs. 3 and 8, said lugs having pivotally secured therein an end of the link 53, the other end of said link being attached to the limb 54 of the bell-crank 55, 85 which is pivotally mounted in the lugs 56, the other member 57 of said bell-crank having pivotally attached thereto the forwardly-extending link 58, which is pivoted to the operating-lever 59, the latter being pivotally mounted in the projection 61 and provided with a handle 62.

63 designates a connecting-rod which is adapted to be secured to the cylindrical portions 31 of the reinforcing devices 29, the latter being attached to the outer row of slice-bars, as will be evident from Figs. 3, 6, and 8, said connecting-rod 63 being continued beyond the lugs 25 of the front slice-bar and having attached thereto the link 64, which is 100 pivoted to the operating-lever 65, the latter being fulcrumed at 60 and provided with a handle 66.

67 designates a latch or locking device which is pivotally supported and has the recess 68, 105 adapted to engage the lug or projection 69, attached to the operating-levers, as will be evident from Figs. 8 and 9.

70 designates the relative position of the boiler-shell or front head of the boiler to the 110 grate, said shell having the bracket 71 attached thereto, whereby the movement of the operating-levers is limited, so that there is no liability of dumping the grate when shaking.

The central portion 72 of the bearing-bars 115 40 is turned cylindrical, while the remainder of the bearing-bar 40 is of hexagonal or similar polygonal shape, so as to engage with and snugly fit the polygonal recesses 26 of the alternate slice-bars b b, as will be understood 120 from Fig. 6, while the remaining alternate slice-bars, as indicated at a, Fig. 6, have the recess 26^X, Fig. 16, which is rounded, so as to rest and rock on the edges 25^X of the polygonal bar 40, wherefrom it will be apparent that 125 when the connecting-rod 51^X is actuated it will rock the slice-bars indicated at a, as seen in Fig. 6, the middle slice-bar having its lugs 25 engaging the transmitter 37 and the second slice-bar a on each side of said middle 130 bar being rocked through the medium of the bar 51^X and the transmitter 37, as is evident. Likewise the four alternate slice-bars marked b (seen in Fig. 6) will be actuated when the

connecting-rod 63 is reciprocated, since said slice-bars *b* fit snugly on the polygonal surfaces of the bearing-bar 40, so that it will be apparent by following out the connections seen in Figs. 3 and 8 that when the levers 59 and 65 are reciprocated in unison the adjacent slice-bars in longitudinal series rock in opposite directions and assume the position seen in Fig. 8, as will be hereinafter explained.

10 Referring now to the mechanism for rocking the rear or right-hand set of slice-bars, (seen in Figs. 2 and 3,) it will be seen that at the rear or right-hand portion of the furnace in said figures is a connecting-rod 74, which is suitably attached either directly to the lugs 25 of the slice-bars or to the cylindrical portion 31 of the reinforcing devices 29, said connecting-rod 74 corresponding to the connecting-rod 51^X. (Seen in Fig. 8.)

20 75 designates a link having one end attached to the lugs 75^X, projecting from the under side of one of the slice-bars seen in Fig. 3, the other extremity of said link being pivotally attached to the member 76 of the bell-crank 76^X, which is pivotally attached to the depending rib 10^X of the tie-piece 9, the other member 77 of said bell-crank having pivotally attached thereto the rod 78, which is actuated by the lever 78^X, as will be understood from Fig. 9, wherefrom it will be apparent that when said rod 78 is reciprocated the slice-bars indicated at *a* in the rear half of the grate will be reciprocated in substantially the same manner as the corresponding slice-bars *a*, (seen in Figs. 6 and 8,) the relative position and manner of attachment of the bell-crank 76^X to the bottom of the contiguous slice-bar and to the rib 10^X being substantially identical to the structure seen at the left of Fig. 8, where the manner of operating the slice-bars, &c., is clearly shown, the slice-bars *b* at the right of Fig. 3 corresponding to and being actuated in the same manner as the bars *b* in Figs. 6 and 8, as is evident.

30 The connecting-rod 79 corresponds to the rod 63 (seen in Fig. 8) and is suitably attached to the lugs or reinforcing devices of the adjacent series of slice-bars *b* and is extended beyond the same, as will be seen at the right of Fig. 3, and has the operating-rod 80 pivotally attached thereto, wherefrom it will be apparent that the simultaneous reciprocation of the rods or links 78 and 80 will perform substantially the same function as the simultaneous reciprocation of the rods or links 58 and 64, (seen in Fig. 8,) the rear or right-hand set of slice-bars (seen in Fig. 3) thus being actuated in substantially the same manner as the forward set, (seen in Fig. 8,) and a detailed or further illustration of the manner of operating said rear slice-bars (seen in Fig. 3) is deemed to be unnecessary in view of the showing in Fig. 8.

40 65 From the construction seen in Figs. 2 and 3 I have obtained excellent results, but have found that in some instances by the employ-

ment of the tie-piece 9 at or near the center of the grate a transverse dead-spot may exist, which under certain circumstances is objectionable.

When it is desired or expedient to dispense with the tie-piece 9, I insert two or more transverse rows of slice-bars in its place, as will be understood from Fig. 5 and also from the bottom plan view of Fig. 4, this being the construction in which I preferably employ the sectional side bars seen in Figs. 13 and 14.

The principle of the invention is identical in Figs. 4 and 5 with the principle illustrated in detail in Figs. 2, 3, 6, and 8, the slice-bars being actuated in opposite directions simultaneously or independently and supported and locked in substantially the same manner as already been explained. It may, however, in some instances be desirable to employ the specific actuating means for the slice-bars seen in Figs. 4 and 5, in which 81 designates a reciprocating connecting-rod, which has one end attached to the member 82 of the bell-crank 83, which latter is mounted on the rock-shaft 82^X, which has its bearings in the lugs 84.

At one side of the furnace, as the lower right-hand side of Fig. 4, the member 85 of the bell-crank 83 has a link 86 connected with the lug 87 of the contiguous slice-bar, while the opposite extremity of the rock-shaft has an arm 85^X, which has a link 86 pivoted thereto, said link being attached to the lug 87 of the adjacent slice-bar, three of the slice-bars, in longitudinal series, being connected by means of a rod 87, which corresponds to the rod 51^X in Figs. 6 and 8, so that when the rock-shaft 82^X is actuated by reason of the intermediate connections to the slice-bars *a* the latter in longitudinal series will rock in unison and independently of or in unison with the adjacent longitudinal series *b*, as will be understood from Figs. 4 and 6, the general arrangement of the relative position of the parts being understood from the construction seen at the right of Figs. 4 and 5, although it will of course be apparent that I do not desire to be limited thereto in every instance.

115 The slice-bars *b*, which correspond to the bars *b*, (seen in Figs. 6 and 8,) are connected by means of the link or rod 88, which corresponds to the rod 63, said rod 88 being pivotally attached to the lugs 25 or the reinforcing devices 29 of the adjacent slice-bars and having the connection 89 pivotally attached thereto, by means of which the slice-bars *b* at the rear or right-hand portion of the furnace are operated, it being understood that the slice-bars *a* and *b* are arranged transversely to the furnace, alternately and in longitudinal series, and adapted to rock alternately in substantially the same manner as indicated in Figs. 6 and 8, certain of the intermediate slice-bars of Fig. 4 being omitted for the sake of clearness of illustration.

90 designates a connecting-rod attached to the lugs 25 or their reinforcing devices 29 and

having the rod or link 91 pivoted thereto, whereby the slice-bars *b*, which alternate with the bars *a* and are arranged in longitudinal series at the front or left-hand portion of the 5 furnace, can be operated in unison, said bars *b* being fitted snugly on the hexagonal or polygonal bars 40, as already explained with reference to Fig. 6.

92 designates a connecting-rod which is attached 10 to the lugs or reinforcing devices of the slice-bars *a*, so that the latter are actuated in unison, the rod 92 corresponding to the rod 51^x. (Seen in Fig. 8.)

93 designates a link which is pivotally attached 15 to the lug 94 of one of the forward slice-bars, said link being pivotally attached to the member 95 of the bell-crank 96, which is fulcrumed on the lug 97, the member 98 of said bell-crank having the rod 99 attached thereto, by which the slice-bars in connection 20 therewith are actuated.

It will be apparent that for the sake of clearness of illustration I have omitted from Fig. 5 some of the links, connecting-rods, &c., 25 seen in Fig. 4, and vice versa; but it is thought that from the foregoing explanation, taken in connection with the detailed structure hereinbefore described, the operation of the slice-bars seen in Figs. 4 and 5 will be 30 clearly understood. It will be understood that although I have shown seven slice-bars mounted on the transverse bearing-bars I need not be limited thereto in every instance, since the number of slice-bars is of course dependent upon the width of the furnace. It 35 will also be noted that the lugs 25 of the two slice-bars *b* on either side of the central bar *a* are shortened, so as to clear the transmitter 37, all of the slice-bars being held at the 40 proper distance apart by any suitable means. It will be apparent that the ports 11 may open at their lower extremities into the ash-pit at either side of the web 10^x, as indicated in Fig. 8, and may discharge through the tie- 45 piece either as indicated in Figs. 1 and 2 or as in said Fig. 8.

The grate may be supported on feet, as indicated in Fig. 1, or it may rest upon hoops, brackets, or similar devices, as is evident.

50 In Fig. 3 I have shown a different manner of applying the transmitter 37 from that seen in Figs. 6 and 8; but it will be apparent that the principle and function of said transmitter are the same in each instance. It will also 55 be evident that, if desired, I may insert longitudinal stationary bars between the slice-bars.

The operation is as follows, the manner of locking or assembling the outer framework 60 of the grate being first described: Referring first to Figs. 2 and 9, the side bearing-bars are first arranged in substantially the position seen, after which the head-pieces or end frames 3 and 3^x are inserted in position, the 65 dovetailed tongues and grooves common to said end frames and side bars interlocking, as shown in Figs. 1 and 9, it being of course

understood that the rear end frame 3^x also interlocks with the side bars in substantially the same manner as indicated in Fig. 9. The 70 key-blocks 6 are next dropped into the position seen in Fig. 2, as is also the tie-piece 9, the latter being held in position by reason of the dovetail-shaped tongues and grooves, wherefrom it will be apparent that the entire 75 framework can be assembled without necessitating the employment of bolts or other extraneous fastening devices. The wedge-shaped blocks or keys 44 having been removed, the oscillatory bearing-bars 40 are dropped into 80 the position indicated in Fig. 6. The slice-bars are now placed in the position indicated in Fig. 6, the end slice-bars *b* being first dropped into place and moved to the position indicated next to the side bars 2 and then the 85 adjacent slice-bars *a*, which it will of course be understood are constructed as seen in Fig. 16, so as to allow of rotation independent from the transverse bearing-bar 42, after which the intermediate slice-bars *b* and the 90 central bar *a* are placed in position, it being of course understood that all the slice-bars *b* have the polygonal recesses 26, which engage snugly with the polygonal bearing-bar 40, so that the latter and the slice-bars *b* oscillate in 95 unison, while the slice-bars *a*, having curved instead of polygonal recesses, can be oscillated on the knife-edges 25^x of the polygonal bar 40, independently thereof, when desired. Prior to the placing in position of the three 100 central slice-bars *a* and *b* (seen in Fig. 6) the transmitter 37 is dropped into the pockets or recesses 36, the reinforcing devices or caps 29^x and 29, having been placed in position, it being noted that the lugs 25 of the central 105 slice-bar *a* engage the transmitter 37, which is preferably square, whereby all the slice-bars *a* rock in unison. The reinforcing devices 29^x and 29 (seen at the left of Fig. 6) are held in position by the plates 38 and the 110 screws 39, while the reinforcing devices at the right of said figure are held in position by the connecting-rods 51^x and 63 and their respective fastening devices.

The manner of making the connection between the respective links, bell-cranks, connecting-rods, and operating-levers has already been fully explained and it is thought will require no further description.

When it is desired to dispense with the 120 central tie-piece 9, the construction seen in Figs. 4 and 5 is employed, in which latter case it will be apparent that there is positively no dead-surface at any point of the grate, and attention is also directed to the 125 fact that in all the constructions shown the grate-surface is normally always substantially on a level, as will be understood from Figs. 5 and 6.

When it is desired to shake the grate, the 130 levers 65 and 59 are operated in unison, wherefrom by following out the various connections it will be apparent that the front sections of the grate will assume the position

seen at the left of Figs. 1 and 8. If it should be desired to rock the rear sections into the position indicated in Fig. 8, it is only necessary to impart a similar movement, as above described, to the levers seen at the left of Fig. 9.

If it is desired to rock one longitudinal series of a grate-section or slice-bar, it is only necessary to lock one of the levers seen in Figs. 8 and 9 by means of the latch 67 and actuate the other lever, whereupon the parts will assume the position as seen at the right of Fig. 1, the desired longitudinal series of slice-bars being oscillated, while the alternate longitudinal series of slice-bars remain substantially horizontal and serve for the time being as dead-bars.

The grate is prevented from being dumped by means of the stop 71, (seen in Fig. 8,) but of course any other equivalent device may be employed.

It will thus be seen from the foregoing that by reason of the links, connecting-rods, and their adjuncts I am enabled to impart three different movements to the different grate-sections, the first position being as shown in Fig. 8 or at the left of Fig. 1, the second position being indicated at the right of said Fig. 1, while the third position is that in which all the slice-bars by the proper manipulation of the operating-levers may be caused to slant or incline in the same direction, as is evident, in which latter position the grate may be dumped.

It will of course be evident that I need not limit myself in every instance in the construction of the slice-bars to the longitudinally-extending serpentine grooves seen in Fig. 10, since I may, if desired, employ the slice-bar 14^x, as seen in Fig. 15, the appearance of the same in plan view being indicated in said figure, said bar having transverse sinuous ports or passages 21^x therein, but being constructed in all other respects similar to the bars seen in Figs. 10 and 16.

It will be evident that the position of the tongues and grooves common to the side bearing-bars and end frames may be transposed without departing from the spirit of my invention.

Having thus described my invention, what I claim as new, and desire to secure by Letters Patent, is—

1. In a grate, an outer frame, the same consisting of side bearing-bars, each having near its ends downwardly-extending pockets, and in their ends inwardly-extending recesses, the latter being at an angle to said pockets, and head-pieces or end frames having tongues engaging said recesses, said frames having inwardly-extending tongues thereon, in combination with key-blocks having tongues and recesses, said last-mentioned tongues being adapted to engage and interlock with the pockets of the adjacent side bearing-bars, and said last-mentioned recesses being adapted to en-

gage and interlock with the tongues of the adjacent end frame.

2. In a grate, an outer frame consisting of side bearing-bars, having in their ends the dovetailed recesses 9^x and pockets 8^x, head-pieces or end frames having the dovetailed tongues 7^x adapted to engage said recesses, and a series of key-blocks 6, said blocks having dovetail-shaped recesses therein, adapted to engage dovetailed tongues on said end frames and the end key-blocks having tongues adapted to seat in said pockets.

3. In a grate, an outer frame consisting of side bearing-bars, having in their ends, the dovetailed recesses 9^x and pockets 8^x, head-pieces or end frames having the dovetailed tongues 7^x adapted to engage said recesses, and a series of key-blocks 6, said blocks having dovetail-shaped recesses therein, adapted to engage dovetail tongues on said end frames, the end key-blocks having tongues 7 adapted to seat in the pockets in said side bearing-bars, in combination with an intermediate tie-piece, and dovetail tongues and grooves common to said tie-piece and side bearing-bars.

4. In a grate, a slice-bar, consisting of a suitable body portion having a convex top and serrations at the side thereof, said serrations terminating below said top, a sinuous or serpentine strengthening-web having similarly-shaped ports on either side thereof and extending through the body of said slice-bar and lugs depending from the latter, a bearing-bar and connections common to said bearing-bar and slice-bar, whereby said slice-bar is adapted to be actuated by said bearing-bar.

5. In a grate, a slice-bar consisting of a suitable body portion, having a convex top and a strengthening-web, located in said body portion, thereby forming ports on either side of said web, serrations in the sides of said slice-bar terminating below the top thereof, shoulders located near the ends of the bars, and lugs depending from said body portion and having a space therebetween, the upper portion of said space being of polygonal shape, and the lower portion of said lugs being concave or recessed and adapted to receive a reinforcing device.

6. In a grate, a slice-bar consisting of a suitable body portion, a serpentine web located thereon, serpentine ports located on either side of said web and extending through said body portion, serrations or teeth on the sides of said body portion, said serrations terminating below the top of the bar and lugs projecting from said body portion and having a space therebetween, the upper portion of said space being of polygonal shape and the lower portion of the space between said lugs being concaved and adapted to receive a reinforcing device.

7. In a grate, a reinforcing device, the same consisting of a disk or plate 30, having the cylinder 31 projecting laterally therefrom, said disk being provided with a curved, hemi-

spherical shell or cap projecting therefrom, in proximity to said cylinder, in combination with a slice-bar, lugs projecting from said bar and adapted to receive the reinforcing device, and fastening devices common to said lugs and reinforcing device.

8. In a shaking-grate, side bars, transversely-extending bearing-bars, having bearings in said side bars, said transverse bars being cylindrical at their intermediate portion and of polygonal shape in cross-section adjacent thereto, a plurality of slice-bars mounted upon said transverse bars, every alternate slice-bar fitting snugly on said transverse bar, and adapted to move in unison therewith, while the other alternate slice-bars are capable of independent movement relative to said transverse bars, and means for actuating said slice-bars.

20 9. In a shaking-grate, side bars, a plurality of transverse bearing-bars, a plurality of slice-bars mounted on said transverse bars, every alternate slice-bar fitting snugly upon said transverse bar and moving in unison therewith, and the intermediate slice-bars being capable of independent movement relative to said transverse bars, reinforcing devices mounted upon each outer pair of slice-bars, the inner pair of said reinforcing devices having 30 the ends of a rod or transmitter seated therein, the latter engaging the depending lugs of the central slice-bar and means for actuating the alternate longitudinal series of said slice-bars independently or in unison.

35 10. In a grate, side bearing-bars, end frames interlocked therewith, transverse bearing-bars each having two longitudinal series of slice-bars mounted thereon, the slice-bars of one series alternating with those of the other 40 series, and means for actuating each of said longitudinal series, so that each pair of adjacent slice-bars may rock in opposite direction to its neighbor, independently of its neighbor, or can remain stationary thus serving as a 45 dead-bar during the oscillation of its neighbor.

11. In a shaking-grate, a plurality of side bars, transverse end frames, therefor, transverse bearing-bars, a plurality of longitudinal series of slice-bars mounted on each of said 50 transverse bars, the slice-bars of one series, alternating with those of the other series one set of slice-bars in longitudinal series, having a connecting-rod common thereto, a link pivoted to one of the last-mentioned series of 55 slice-bars, and a bell-crank having a member suitably fulcrumed and pivoted to said link, the other member of said bell-crank having means attached thereto for actuating the same, in combination with a connecting-rod 60 common to the links of another series of said slice-bars, a link pivotally attached to said connecting-rod, and means for enabling each of the longitudinal series of said slice-bars to be operated independently or in unison.

65 12. In a grate, an outer framework, consisting of side bearing-bars, one of said side bars having a tongue projecting therefrom,

and a head on the end of said tongue, said tongue and head being adapted to seat in similarly-shaped recesses in a contiguous bar, a 70 ledge projecting from the recessed bar and adapted to support the bar or section, provided with said tongue and head, said latter bar having its under portion cut away for the reception of said ledge, and the parts of the 75 frame being loosely connected whereby expansion is permitted and displacement of said bars is prevented.

13. In a grate, an outer framework consisting of side bearing-bars and end frames, 80 interlocking devices common thereto, said side bearing-bars being made in sections, one of said sections having the tongue 47 and head 48 adapted to seat in a similarly-shaped recess in a contiguous section and said first- 85 mentioned bar having a cut-out portion formed by the walls 49 and 50, said cut-out portion being supported on the ledge 51 of said recessed section, said sections being loosely connected whereby expansion is permitted 90 and displacement of said bars is prevented.

14. In a shaking-grate, a plurality of side bars, end frames and interlocking devices therefor, a series of transverse bearing-bars, 95 each of the latter having two series of slice-bars carried thereon, the slice-bars of one series alternating with those of the other series, means for enabling each of the two series of said slice-bars to be independently operated 100 so as to move either in the same direction or in opposite directions, and locking devices for said actuating means.

15. In a grate, transverse bearing-bars, suitably supported, a plurality of slice-bars 105 mounted thereupon, every alternate slice-bar rocking in unison with its bearing-bar, and the other slice-bars rocking on said bearing-bar as an axis, the slice-bars adjacent to the central slice-bar having shortened lugs, a 110 transmitter suitably supported, the lugs of said central bar engaging said transmitter, and means for actuating said slice-bars.

16. In a grate, the combination of bearing-bars suitably supported, two series of slice-bars carried on each of said bearing-bars, the slice-bars of one series alternating with those of the other series, and means by which the slice-bars of the two series may be rocked in the same direction or in opposite directions. 120

17. In a grate, the combination of bearing-bars suitably supported, two series of slice-bars carried on each of said bearing-bars, the slice-bars of one series alternating with those of the other series, lugs projecting from said 125 slice-bars and provided with reinforcing devices and connections common to said reinforcing devices in combination with means by which the slice-bars of the two series may be rocked in the same direction or in opposite directions.

18. In a grate, transverse bearing-bars, suitably supported, each of said bars having two series of slice-bars carried thereon, every al-

ternate slice-bar rocking in unison with its bearing-bar and the other slice-bars mounted on the latter, rocking on said bearing-bar as an axis, the slice-bars adjacent the central slice-bar having shortened lugs, reinforcing devices secured to the outer pair of slice-bars at each side of the grate, a transmitter having its ends seated in the inner pair of reinforcing devices and engaging the lugs of the central slice-bar, and actuating means attached to said reinforcing devices.

19. In a grate, a reinforcing device, the same consisting of a plate, having a cylinder or member projecting laterally therefrom, and a curved cap projecting from said plate in proximity to said member, in combination with a slice-bar having lugs depending therefrom, the inner lower faces of said lugs being recessed for the reception of said member,

while the lower extremities of said lugs are curved to conform to the inner surface of said cap, an actuating-bar adapted to be secured to said laterally-projecting member of the reinforcing device and fastening means common to said bar and member. 25

20. In a grate, an oscillating slice-bar, consisting of a suitable body portion having a convex top, solid end portions, and serrations at the sides of said body portion, said serrations terminating below said top, a strengthening-web located within the sides and ends of said body portion, thereby forming ports extending through said slice-bar, and lugs depending from the latter. 30
